TILING

Carl G. Muench, New Orleans, La., assignor to
 The Celotex Corporation, Chicago, Ill., a corporation of Delaware

Application May 16, 1940, Serial No. 335,437

1 Claim. (Cl. 144—309)

This invention relates to tile, particularly to tiling for an ornamental ceiling or wall surface, and has for its principal object to provide a tile and structure made therewith which will be cheap to manufacture and more convenient in use than those heretofore proposed.

Another object of the invention is to provide a structural member with a tongue and groove edge construction with the groove formed by rear and front lips of unequal length, the rear lip thereof providing exposed nailing and a protective edge and the front lip a support for the complementary formed tongue which also provides a protective edge for the member, and when contiguous members are erected a concealed nailing or securing joint is formed.

Another object of the invention is to provide a novel tile having an inclined nailing surface and a horizontal supported surface at an opposite edge thereof, whereby a complementary tongue comprising the horizontal supported surface which is formed is adapted to be readily inserted into a V shaped groove of a contiguous tile provided by the inclined nailing plane and a horizontal supporting surface similarly formed as the horizontal supported surface to support the contiguous tile in its erected position.

A further object of the invention is to provide a novel tile construction wherein the elongated lip providing the inclined nailing surface as well as the tongue and its horizontal supporting plane provides a protective edge about the ornamental face of the tile, as well as a concealed or blind nailing joint when erected in abutting relationship with contiguous tile.

With these and other objects in view, the invention resides in the novel details of construction and combination of parts as will be disclosed more fully hereinafter and particularly pointed out in the claim.

Referring to the accompanying drawing forming a part of the specification and in which like numerals designate like parts in all the views:

Figure 1 is a view in elevation illustrating tile applied by the use of furring strips to joists or to a plastered wall construction;

Figure 2 is a perspective view, partly in section, of the tile looking at the tile as applied to a ceiling;

Figure 3 is a vertical sectional view along the line 3—3 of Figure 1 and looking in the direction of the arrows showing the details of the blind nailing joint construction; and,

Figure 4 is an enlarged sectional view illus-

trating the blind nailing joint construction and the induration at the joint.

This invention is directed to a tile so constructed that a plurality of similar tile may be laid in edge abutting relation in the construction of floors and walls, each tile having a blind nailing joint construction whereby each tile may be affixed into the floor, wall, ceiling construction or the like without the securing means showing at the surface of the tile. It is preferred that each tile has an interlocking and/or wedging joint construction about the edges thereof so that contiguous tile, when in abutting relation, will form a concealed or blind nailing joint construction.

Another important feature of the invention is that in erecting the tile they may be started either from the edge of the room or from the center of the room, depending upon the pattern

20 to be laid. Each tile may be of any suitable material, either of one piece construction or made as a laminated structure, and may be of dimensions preferably multiples of 12" or 16", whereby with the use of different sizes of tile, variegated patterns may be formed for an ornamental wall or ceiling.

Referring to Figures 1 and 2, tile 10 are erected preferably, as best illustrated in Figure 1, by first 30 erecting furring strips 11 to joists 12 in a new ceiling or a wall construction or the tile may be directly affixed to furring strips 11 which are directly affixed to plaster 13 or the like construction, the latter, particularly where the tile are used for renovating the surface of a room. Al-

though this form of tile is used particularly for 35 providing ornamental surfaces of the walls and ceiling of a room, obviously the same construction may be used equally as well for laying tile on a floor construction. It is preferred that the tile 10 shall be square in shape, though tile of other

40 shapes may be used or the tile may be in various multiples of a unit dimension such as 6" or 8" and suitably combined for forming various geometrical patterns. The upper or exposed face of each tile may be plain or ornamented and either planar or embossed, and the tile illustrated in 45 Figure 1 are formed with a chamfered edge 14 to make a more pleasing appearance while reducing to a minimum the possibility of chipping of the edges or of presenting sharp edges in the finished surface of the tiling.

Referring to Figures 2 and 4, the preferred 50 form of the tile 10 and its joint construction will be described in detail. The edges of the tile are preferably formed with a modified form of tongue

and groove, as best illustrated in Figure 4, so that a blind nailing joint construction is formed. It is preferred that each tile shall have two adjacent edges with a modified tongue construction 15 while the other two adjacent and opposite edges are formed with a modified groove construction 16. In the preferred form of the tile construction, the thickness of the tile is substantially one-half of an inch. In describing the various layers making up the modified tongue and groove construction, for the purpose of description, each tile will be described as formed in three layers, and each layer may be considered as substantially one-third of the thickness of the tile. The tile is preferably bevelled along its face edges to a depth of one-third the thickness of the tile, as illustrated at 14, Figures 1, 3 and 4. The tongue construction and the groove construction 15 and 16 respectively, each form another one-third of the thickness of the tile to give rigidity to the tongue and groove construction. The tongue construction 15 has a tongue 17 having one face, that directed toward the exposed face of the tile formed to provide a horizontal supported surface 18, parallel to but rearwardly of the tile face. The opposite face or rear face of the tongue 17 has an inclined notch portion 19 rabbeted or recessed inwardly from the rear face of the tile and complementally formed with respect to the inclined nailing surface 20 constituting the front face of the rear lip defining the groove 16. The surface of the front lip opposite to the rear lip providing the inclined nailing surface of the groove construction 16 is horizontally formed as at 21 to provide a horizontal supporting surface for the tongue 17 of the contiguous tile and is complementally formed with respect to the horizontal surface 18 thereof. The increased thickness formed at the blind nailing joint, as at 20, allows for the necessary frictional gripping of the material to the nails 22. When erected as illustrated in Figure 3 with the nails 22 driven through this portion of the increased thickness, the nail 22 and the tile 10 are affixed to a furring strip 11.

On tile, the modified groove constructions 16 are formed so that they are complementary with the tongue constructions 15 which are opposite to and adjacent to each other so that when contiguous tile are abutted together form what is known as a blind nailing construction. The modified groove construction 16 is chamfered as at 14 similar to the chamfer formed at the tongue construction 15. The groove construction 16 has a groove 23 complementally formed with respect to the tongue 17, that is, there is the horizontal surface 21 corresponding to the similarly formed horizontal surface 18 of the tongue construction 15. The inclined blind nailing surface 20 of the groove 23 is complementally formed with respect to the notch or recess 19 of the tongue construction 15. As illustrated in Figure 4, it is obvious that with the construction illustrated, a neat as well as concealed joint is formed when contiguous tile with complementary edges are abutted together.

With this novel form of joint construction, it is evident that, as the tile 10 is erected in place and the nails 22 are secured along the tongue construction and driven through the thickened portion, as illustrated in Figure 3, the tile is firmly affixed in place and the next contiguous tile may be erected and supported by the first erected tile without nailing the edge which is being applied. Therefore, the concealed nailing

construction serves as a support for contiguous tile when erected in this manner. As the contiguous tile are erected in place, as illustrated in the enlarged view, Figure 4, the face 18 of the tongue 17 slides over the horizontal surface 21 of the groove 23 so that the surface 21 of the groove 23 serves to support the contiguous tile due to surface 18 resting on the surface 21 and is therefore supported by the groove construction of the tile which is affixed to the furring strip. The description which has been given obviously refers to a construction where the tile are applied to a ceiling construction, and obviously when they are supported in a floor construction, the inclined nailing surface 20 will support the complementing surface of a tongue of a contiguous tile while it is being nailed in position by means of the groove construction opposite thereto.

In connection with tile provided with the novel tongue and groove described, it is evident that the tile may be rapidly applied and that when erected, the securing means are concealed; and, at the same time, any expansion or contraction occurring in individual tile is free to take place due to the construction involving the unsecured edges opposite to those which are secured. Also the novel tongue and groove construction prevents breathing of the joints because of the interfitting tongue and groove construction, and it also provides an ornamental joint in that there are no open spaces where the tile are abutted together and shadows from the bevels tend to conceal the joints. As illustrated in Figure 4, the tile have been shown as formed at the edges which are grooved with the bevels 14 meeting the horizontal surface 21 of the groove 23 in a sharp edge. When used with materials such as felted fibre board, this feather edge is somewhat objectionable and this may be overcome by having the chamfer stop before it meets the respective horizontal surfaces 21 and 18 of the complementally formed tongue and groove constructions 15 and 16 respectively. With certain forms of material, however, this feather edge is not objectionable.

The tile which has been described with reference to Figures 2 and 4 may be applied using furring strips 11 spaced on the same centers as the dimensions of the tile and these are preferably 12" or 16", or multiples thereof, depending upon the geometrical pattern desired. In applying the tile, the center lines of the wall or ceiling are first found and the odd dimensions from the edges are laid out so that the tile may be laid beginning with the odd dimension size tile, that is, the tile are so laid that the tile are started from the edges of the wall or ceiling surface rather than started from the center of the room. In laying the tile in this manner, it would then be necessary to apply the tile as illustrated in Figure 3, beginning from the right hand side of the room and working to the left across the entire surface to which the tile are being applied, ending up with the tile as illustrated in the left hand side of Figure 3, if the dimensions of the room are such that the tile come out even. If the width of the surface is not a multiple of the dimension of the tile, the outer or edge rows of the tile may be suitably cut to the proper width and provide a suitable border along the edges of the installation.

The furring strips should be carefully laid out so that the joints as the tile are applied fall over furring strip. A disadvantage in applying a ceiling or wall laid in this manner is that usually due

to inaccurate measurements and because of difficulties inherent in application, the dimensions are not maintained and the pattern will be poorly applied particularly if an ornate geometrical pattern is being applied. In applying the tile, the tile is firmly nailed along the inclined nailing surface 20 of the modified groove construction 16 as illustrated in Figure 3. It is only necessary to nail along the groove construction of one edge of the tile since the groove construction along the edge of the tile is sufficiently strong to support the tile because of the short span of 12" or 16" between the furrowing strips. If, however, tile of multiples of these dimensions are used for some of the tile, it would be preferred to apply additional furring strips between those extending across the room and affix the tile thereto, the remaining tile may then be erected in the same manner previously described. Although the erection of the tile has been described with reference to nailing it is apparent that the tile may be equally as well applied by the use of a suitable adhesive by the methods well known in the art. It is obvious that the construction illustrated and described provides a novel tile which is simple and cheap to manufacture as well as to install.

The tile may also be formed into other patterns than that illustrated in Figure 1, particularly in what is known as a diamond pattern where in the center lines of the room are struck, and the tile are applied in end to end relationship with the diagonal of the tile in alignment with the center line struck and in end to end relationship at the opposite corners. The furring strips for this pattern are also laid on 12" and 16" centers at an angle of 45° with respect to the center line struck if the tile are square in shape, and the tile are nailed to the furring strips in the same manner as previously described. It is obvious that other methods of applying the tile are equally applicable with this novel form of blind nailing joint construction.

The novel blind nailing joint construction has preferably been generally described without regard to the material used for the tile but when the tile are fabricated from felted fibrous ligno-cellulose material a weakened joint is formed because of the nature of the material. This particular form of joint, however, has been primarily developed for the use of tile or panels fabricated from felted fibrous ligno-cellulose material, preferably bagasse, the ligno-cellulose material being sized and treated against fungus and insects by any of the methods and treatments well known in the art and which are not necessary to be described here for the understanding of this invention. It has been found, however, that the material when manufactured commercially, and particularly because of the character of the felted fibrous material after the tongues and grooves have been formed, there is some tendency for the edges of the tongues and grooves to become upset and rough and ragged because of the thinness of the material but more so because of the character of the material from which it is formed. It has been found also that this structural difficulty in the joint construction due to the nature of the material forming the tile may be readily overcome by indurating the edges where the tongue and grooves are formed with shellac, glue size, or resin. This induration of the material may be done by impregnating the sheets from which the tile are fabricated, such impregnation being in relatively narrow intersecting strips forming the squares where the tile are to be cut,

or the edges of the tile may be individually dipped and indurated after fabrication by the usual double end tenoner or tile machine. In the usual process, individual squares from which the tile are fabricated, are stacked and then automatically run through a double end tenoner or tile machine to form the bevels and joints thereof in successive passes through the machine, or through successive machines.

10 As illustrated in Figures 3 and 4, a hardening and toughening material as this induration 24 may be with a glue size, shellac, or resin and is preferably such so that it extends a substantial distance from the edge of the tile and preferably 15 as illustrated in Figures 3 and 4, so that it strengthens the entire tongue and groove construction of the tile. This induration preferably comprises the impregnation along the edges of the tile with a hard wood pitch and synthetic 20 resin of such a formula that the resulting induration will leave the tile firm and strong.

The preferred induration, in order to obtain adequate shear strength of the felted fibrous material at the joints to strengthen the tongue and groove and also to resist board shrinkage stresses 25 particularly in large tile forms or panels, is a dilute glue solution brought into the felted fibrous material forming the tile by means of a suitable wetting agent.

30 The following solution has been found to give satisfactory hardness and strength to the tongue and groove structure forming the edges of the tile, and it comprises the following ingredients and is compounded as follows. First, 1 part of Armour 35 #3 grade ground bone pearl glue is dissolved in 5 parts of water. In order to bring the ground glue into solution, it is preferred to first soak the glue in 1 part of cold water for a few hours and then add the remaining 4 parts of water. The temperature of the solution should be raised to about 165° F. and should be maintained at this point. To the above solution is added a wetting agent 40 preferably a 2% "Duponal W. A." which is a sodium lauryl sulphate. This wetting agent has a 45 50% active agent and the 2% which is added is based upon the water content of the glue.

The indurating solution as it is applied must be maintained at a temperature above 150° F. and below 170° F. The edges of the tile may be indurated by applying the solution to the tongues and grooves of the tile by dipping the edges into the indurating solution for from 5 to 10 seconds or by spraying with a continuous stream for the same period of time. In order to avoid a difference in texture at the joint between the contiguous tiles, it is preferred to indurate only the tongue construction and the groove construction of the tile without indurating the surface layer of the material forming the tile. Although this method of induration is preferred, it is not essential and the edge of the tile may be indurated so that the chamfered edges are indurated. A preferred practice in order to avoid a tendency to reduce the width of the groove when the indurating solution shrinks on the inside faces is to indurate the lower lip of the groove completely while leaving the face which is exposed at the tongue construction free from the indurating solution. The cross hatched area of Figure 3 illustrates the preferred depth of the induration on both the tongue and groove and this induration may extend completely across the tongue and groove construction from one face of the tile to another or the face which is exposed may have the induration

extend to within a short distance from the face of the tile.

The apparatus for spraying the tile preferably comprises a pipe or other similar apparatus from which the solution is sprayed from a series of $\frac{1}{16}$ inch holes spaced $\frac{3}{4}$ of an inch apart. The indurating solution may be kept away from the exposed surface of the tile or ornamented face of the tile by means of a suitable gasket which presses against the edge of the tile as they are being sprayed. It is important that the edges of the tile shall be kept in firm contact with the gasket during the spraying period of from 5 to 10 seconds. The indurating solution is preferably maintained at the desired temperature of 160° F. to 165° F. by means of a water bath, the excess solution draining off into the reservoir of the pump which forms part of the apparatus for spraying the solution.

The opposite edges of the tile may be simultaneously and continuously sprayed in a separate operation from that of coating the tongues and grooves on the tile or it may form a part of the apparatus of the double end tenoner machine for forming the tongues and grooves. In this case, the cost of spraying is reduced as the indurating may simultaneously take place as the modified tongues and grooves are formed. The edges of the board may also be suitably protected by a gasket in the same manner as that previously described above only that the exposed edges of the tile are blocked off and the spray is kept away. Any excess solution in this continuous method is carried off and may run into a suitable trough where it is carried into the reservoir of the pump which distributes the solution.

After the indurating solution has been applied, the tile may be stacked as the edges will not stick together. It is, however, preferred to stagger them to permit better access of the air for drying the indurating solution. To satisfactorily air-dry the edges, it takes substantially two days to thoroughly dry the indurated tongue and groove edges of the tile.

It has been found that by so indurating the tongue and groove construction of felted fibreboard, preferably of felted bagasse fibres, that there is obtained a tensile strength in the tongue equal to substantially three-quarters of the tensile strength of the full thickness of the felted fibreboard. Without induration, the joints shear at a load that is generally less than one-third of that required to rupture the felted fibreboard. It is therefore obvious from the above disclosure with respect to the method and solution for indurating the tongue and groove construction of the tile that adequate shear strength at the joints has been obtained to particularly resist the shrinkage stresses of the tile, particularly if the edges of the tile besides being blind nailed are adhesively secured together.

Having thus described the invention, particularly with respect to the novel form of blind nailing joint construction and method of erecting the

tile using this novel construction, it is obvious that a simple form of tile has been disclosed which may be cheaply manufactured and easily installed without the use of highly skilled labor.

5 Furthermore, a novel method has been disclosed for impregnating or indurating the edges of the tile so that it will not be damaged in shipment or in erection, and particularly to strengthen the tongue and groove construction of tiles formed from felted ligno-cellulose material, so that the edges will not be damaged in shipment or erection to detract from the appearance of the finished tiling construction after erection. Tile manufactured in this manner are usually fabricated from large sheets of felted fibrous material and particularly after the material has been painted, that is, the surface of the material is painted as the material is being fabricated in continuous sheets, but before it has been conveyed through the drier for drying in the preferred process of fabricating the material. In this method of painting and fabrication, an ornamental prepainted surface is provided but the bevels 14 are in the natural color of the material although it is obvious that tile may be fabricated with the surface in the natural color of the material. It is obvious, however, that the bevels may be painted after the tile are fabricated and also that additional coats of paint may be applied to the surface of the tile after the fabrication of the edges which form the blind nailing joints. This is particularly necessary when the edges of the tile are indurated, although not essential.

20 35 It is also obvious that those skilled in the art may vary the details of the construction and arrangement of the tile without departing from the spirit of this invention, and therefore it is desired not to be limited to the exact foregoing description except as may be demanded by the claim.

40 What is claimed is:

The method of forming from felted fibrous material a structural member having indurated complementally formed interfitting edges, which 45 comprises: indurating in a predetermined intersecting geometrical pattern narrow linear sections of a width in excess of the overall width of the complementally formed interfitting edges throughout the thickness of the felted fibrous 50 material forming indurated, intersecting sections in a predetermined geometrical pattern, severing the material substantially medially of the width of the indurated narrow linear sections and forming complementally formed interfitting edges 55 along the edges of the indurated sections whereby the complementally formed interfitting edges of the structural member are indurated, the structural member having the aforesaid edges strengthened and rigidified by the induration thereof and adapted to be erected with its edges complementally engaged with complementally formed structural members.

CARL G. MUENCH.
